UNITED STATES PATENT OFFICE.

WILLARD E. BARCUS, OF VINELAND, NEW JERSEY.

MOLASSES-MEASURE.

SPECIFICATION forming part of Letters Patent No. 274,698, dated March 27, 1883.

Application filed August 16, 1882. (No model.)

To all whom it may concern:

Be it known that I, WILLARD E. BARCUS, of Vineland, in the county of Cumberland and State of New Jersey, have invented certain new and useful Improvements in Molasses-Measures, of which the following is a full, clear, and exact description.

The object of this invention is to provide a measure for molasses and other viscous substances which shall have attached means whereby it may be rapidly and thoroughly cleansed.

In dispensing molasses in grocery stores, by the measures as ordinarily constructed, there is much time lost in clearing the measures of their entire contents, owing to the thick and sticky nature of the molasses or syrup, and either the customer is forced to lose a large amount of time by waiting for the measure to be cleared, and even then loses some of the contents, or is obliged to leave behind him much of the material for which he has paid. So important is this loss of time or material, or both, that the sale of molasses or syrups is seriously curtailed in the winter season, when such material is more than ordinarily sluggish. There is also a frequent necessity for removing the crust which forms around the sides and edges of the measures, and for washing and draining them out to fit them for repeated use, beside which they cause much filth and dirt about the place in which they are used.

My invention removes all these and other objections; and it consists in a molasses or other like measure provided with a discharging follower or cleaner controlled by a spring, and an internal scraper or clearer capable of operation from the exterior of the measure, whereby the measure and its nozzle may readily be cleared.

The invention also consists in various details and novel constructions and combinations of the same, whereby the full advantages of my improved measure are thoroughly attained.

Reference is to be had to the accompanying drawings, forming a part of this specification, in which similar letters of reference indicate corresponding parts in all the figures.

Figure 1 represents a vertical section of my improved measure as filled with molasses to its intended capacity. Fig. 2 is an inverted

plan of the same, showing a jointed rod, by which the plunger is drawn outward and the scraper is rotated, as folded up out of the way under the fixed bottom of the measure. Fig. 55 3 is a top view of the measure. Fig. 4 is a plan view, in part, of the follower, together with the scraper and rod for operating the same; and Fig. 5 is a sectional view of a reducing discharge-nozzle.

A indicates the body of the measure, which is made sufficiently deep to provide for the arrangement within it of a follower or cleaner, B, and a spiral spring, C, below the follower. This spring should be of sufficient strength 65 that, when released, it will not only force the follower up to the top of the can or measure, but also cause the follower to drive out the molasses or syrup through a nozzle, F, on the lid E when the measure is inverted for the 70 purpose. Said follower B has a packing, b, of felt or other suitable material, to give it a close fit and wiping action within the measure.

The top c of the can has an enlarged central opening, d, in it, which serves, when the lid E is opened, and the follower B is drawn down to its extreme point, as shown in Fig. 1, to allow of the measure being filled with molasses, or, rather, with a measured quantity thereof, in the space between said lowered follower and 80 the top of the can. The same metal that is removed from the top of the can to make the hole d is soldered to the under side of the lid, and has an aperture, e, made in it to form a communication with a delivery-nozzle, F, fast 85 on the outside of the lid. By this construction of the lid E, which may be hinged at f, and be secured by a catch, g, the lid not only has a re-enforcing plate, h, on its inside, but a flush surface is provided on the interior of the 90 top c for a scraper, which will be hereinafter described, to work over or against.

The bottom i of the can is a raised one—that is, it is of inverted-cup shape—the reason for which will be presently explained.

Projecting up through the follower B, also through a hub or hollow stop, k, from which braces l are projected to stiffen and steady the follower, and through the bottom i of the can, is a jointed rod, G, fitted with a handle, m, on its outer end, exterior to the bottom of the can, and with an attached scraper, H H', on its in-

ner end, within the measuring chamber or space of the can. This scraper is of right-angled shape, being formed of two wings, the one H of which is arranged to sweep over the inner 5 surface of the follower B and under side of the top c and re-enforcing plate h , when the follower B is forced outward by the spring C , till arrested by a set-off, n , in the upper part of the cam, and the other wing, H' , of which is 10 arranged to sweep round the interior of the nozzle F from one side to the other of a fixed wing, I , projecting radially within and attached to the nozzle. This action of the scraper is effected by turning the jointed rod G by its 15 handle m . The fixed wing I is hollow and open to the atmosphere on the interior of the nozzle, throughout the length of the latter, to provide for the escape of air from the vessel, through a hole in the top of which the molasses 20 is poured from the measure when inverted for the purpose. One or more smaller funnels, F' , Fig. 5, may severally be inserted in the lid-funnel F to adapt the measure to receptacles having different-sized filling-holes.

25 The bottom i of the can is provided with one or more apertures, o , either one of which may or may not be closed by a slide, p , to provide for the escape of drip and ingress of air back of the follower. Furthermore, the rod G is or 30 may be fitted with a spring or other catch, J , to lock and hold the follower B against the pressure of its spring when the measure is drawn outward to receive the molasses.

35 A wing or bar, I' , corresponding in position with the fixed wing I in the funnel, is arranged within the can immediately beneath its top c . This wing I' extends nearly half-way across the can. When using the measure the follower or cleaner B is drawn outward to the 40 position represented in Fig. 1, and locked by the spring-catch J shooting under the bottom i . The lid E is then thrown back or open, and the measure filled with molasses through the enlarged opening d in its top, after which said 45 lid is closed and secured, and the measure inverted and its nozzle F inserted within the neck or receiving-aperture of the vessel into which the molasses is to be delivered. The catch J is then pressed inward by the thumb, 50 which allows of the spring C forcing the follower or cleaner B inward till arrested by the set-off n , to discharge the molasses from the measure into the vessel placed to receive it. In this action of the follower the rod G , with 55 its attached scraper $H H'$, is carried along with the follower, after which said rod is turned by its handle m to rotate the scraper $H H'$ only as much short of a whole revolution as the thickness of the fixed wing I in the funnel. This clears the remaining molasses from 60 the can between the follower and top c of the can and within the funnel F , and, in conjunc-

tion with the action of the follower when forced inward by its spring, causes the whole of the measured quantity of the molasses to be discharged, and leaves the measure clean for subsequent use.

65 The jointed construction of the rod G provides for its being folded up and secured by the catch s within the raised bottom i after the follower or cleaner B has been drawn outward to the position shown for it in Fig. 1. Said rod is represented as thus folded and secured in Fig. 2 of the drawings.

70 It may here be observed that the follower, while performing its functions of cleaning the can or measure, also expedites the discharge of the contents. It should be noticed that the bottom i is held to the body A by clasps, to provide for the removal of the body and inside 80 devices when necessary.

75 Having thus described my invention, what I claim as new, and desire to secure by Letters Patent, is—

85 1. In a measure for molasses and other viscous substances, the combination, with the body of the can or measure and its top, of a follower or cleaner of like area with said body, a spring for forcing said follower inward, a rod or means for drawing the follower outward 90 against the pressure of the spring, and a scraper capable of being turned or rotated from the exterior of the measure, and arranged for operation within the upper part of the measure, substantially as specified.

95 2. The combination, with the body A , its top c , and lid E , of the funnel F , having an attached radial wing, I , the fixed wing I' , within the body, the follower or cleaner B , and the rotary scraper having wings $H H'$ at right angles, or thereabout, to each other, substantially 100 as described.

105 3. The lid E , provided with a funnel, F , and fixed hollow wing I , arranged within the funnel and open to the exterior in the direction 110 of the length of the funnel, substantially as described.

110 4. The jointed rod G , having an attached scraper $H H'$, in combination with the follower or cleaner B and its spring C , substantially as shown and described.

115 5. The body of the can having a raised or hollow bottom, i , in combination with the jointed rod G , having an attached scraper, $H H'$, and the follower or cleaner B , with its spring C , substantially as specified.

6. The combination of the catch J with the rod G , the bottom i of the can or measure, the follower B , the spring C , and the scraper $H H'$, essentially as described.

WILLARD E. BARCUS.
